TREE SAP COLLECTING SPIGOT

Clement Metivier and Jean-Marie Chabot, St. Damien, Bellechasse County, Quebec, Canada, assignors to Les Industries Provinciales Limitee, St. Damien, Bellechasse County, Quebec, Canada

Filed May 30, 1975, Ser. No. 582,395

Term of patent 14 years

Int. Cl. D9—02; D23—99
U.S. Cl. D23—32

FIG. 1 is a perspective view of a tree sap collecting spigot, showing our new design;
FIG. 2 is a side view thereof;
FIG. 3 is a top plan view thereof;
FIG. 4 is a rear view thereof; and
FIG. 5 is a bottom plan view of the spigot.
We claim:
The ornamental design for a tree sap collecting spigot, as shown.
